RAILWAY TRAFFIC CONTROLLING APPARATUS

Original Filed May 5, 1926

UNITED STATES PATENT OFFICE

HERBERT A. WALLACE, OF EDGEWOOD, PENNSYLVANIA, ASSIGNEE TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Original application filed May 5, 1926, Serial No. 106,871. Divided and this application filed August 5, 1929. Serial No. 383,732.

My invention relates to railway traffic controlling apparatus, and particularly to apparatus comprising governing means controlled by energy in the trackway. More specifically my present invention relates to the means for supplying such energy to the rails.

One purpose of my invention is the provision of novel means for supplying energy to the track rails, so that uninterrupted alternating current is normally supplied to the rails, but that under certain conditions periodically interrupted current is supplied to the rails, the characteristic of the periodic interruptions being controlled in accordance with traffic conditions.

The present application is a division of my co-pending application, Serial No. 106,871, filed May 5, 1926, for railway traffic controlling apparatus.

I will describe one form of trackway apparatus embodying my invention, and will then point out the novel features thereof in claims.

The accompanying drawing is a diagrammatic view illustrating one form of trackway apparatus embodying my invention as applied to two parallel tracks connected by crossovers.

Referring to the drawing, the reference characters *d* and *e* designate two parallel railway tracks along which traffic normally moves in the direction indicated by the arrows. Track *e* is divided into two track sections *G*—*H* and *H*—*J* by means of insulated joints 2. The portion of track *d* which is opposite sections *G*—*H* and *H*—*J* is insulated from the rest of track *d* by insulated joints 2 to form a track section *E*—*F*. Section *G*—*H* is connected with section *E*—*F* by means of a crossover designated in general by the reference character *g*, the switches of which are operated by means not shown in the drawing and forming no part of the present invention. A circuit controller designated by the reference character *W^g* is controlled in accordance with the positions of the switches which connect the crossover *g* with the two track sections. The position of the switches of crossover *g* for which the circuit controller *W^g* is closed is indicated in the wiring diagram by

letters inclosed by circles which are in turn designated by the reference character *W^g*. For example, on the left-hand side of the sheet close to relay *Z^g* are two contacts on circuit controller *W^g*. The upper one of these contacts is indicated by a circle inclosing the letter *R*, and the lower contact is indicated by a circle containing the letter *N*. These symbols mean that the lower or normal contact *N* is closed when the switches of crossover *g* are in their normal positions, that is, when these switches are in such positions that traffic can proceed on track *e* through section *G*—*H*. When the switches of this crossover occupy their reverse positions, however, to permit traffic to move from section *G*—*H* into section *E*—*F* over the crossover *g*, the other or reverse contact designated by the reference character *R* is closed.

In similar manner a crossover *h* connects section *E*—*F* with section *H*—*J*, and the switches of this crossover control a circuit controller *W^h*. The contacts of this circuit controller are designated on the drawing by symbols similar to those just explained in connection with the circuit controller *W^g*. It will be noticed that certain of the contacts of circuit controllers *W^g* and *W^h* are marked "CR". This means that the contacts so designated are closed when the associated switches are in the reverse position, and remain closed when the switch moves away from the reverse position toward the normal position until the switch is past the center or "C" position. In similar manner contacts marked "CN" are closed when the switch is in the center position, the normal position or any position between these two.

Current is at times supplied to the rails of each section of tracks *d* and *e* by means of a transformer designated by the reference character *T* with an appropriate distinguishing exponent, and having its secondary 3 connected across the rails adjacent the exit end of the corresponding section in series with the usual impedance 5. Current is at times supplied to the primaries 4 of these transformers by means which I will describe hereinafter. Each section is further provided with a track relay designated by the reference character 100

R with an exponent corresponding to the location and connected across the rails adjacent the entrance end of the section.

Traffic entering stretch d is governed by 5 a trackway signal r^E , and traffic entering stretch e is governed by a similar trackway signal r^G . As shown in the drawing each of these signals r is located adjacent the entrance end of the stretch of track which it 10 governs, and comprises a semaphore arm capable of assuming three positions to indicate "proceed", "caution" or "stop", but this particular location and form are not essential to my invention. In actual practice the signals 15 r will usually be controlled manually from a remote point such as an interlocking cabin so that they normally indicate stop but can be caused to indicate caution or proceed when the operator in the cabin wishes to permit 20 traffic to enter the stretch of track governed by these signals. When a train passes the signal, the indication of the signal immediately changes to stop. Associated with each 25 of the trackway signals r is a circuit controller designated by the reference character U with the same exponent as that applied to the signal, and arranged to be closed only when the signal gives a proceed or caution indication.

30 Associated with each track relay R is a stick relay designated by the reference character Z with the same exponent as that applied to the track relay. Referring particularly to stick relay Z^G , this relay is provided 35 with a pick-up circuit which may be traced from terminal a of a suitable source of current, through back contact 94 of track relay R^G , wires 95 and 96, circuit controller U^G controlled by signal r^G , wires 97 and 98, winding 40 of relay Z^G and wire 99 to terminal b of the same source of current. This circuit is closed only if relay R^G becomes de-energized when signal r^G indicates proceed or caution. But if the de-energization of relay R^G results 45 from the entrance of a train into section G-H, signal r^G goes to stop as soon as the train passes the signal, thereby opening circuit controller U^G and interrupting the pick-up circuit just traced. The relay Z^G , having 50 become energized, is maintained in its energized condition over a stick circuit which passes from terminal a, through back contact 94 of relay R^G , wires 95 and 100, front contact 101 of relay Z^G , wires 102 and 98, winding 55 of relay Z^G and wire 99 to terminal b. Relay Z^G having once been energized, therefore, is maintained in its energized condition as long as relay R^G remains de-energized.

60 Stick relay Z^E is provided with one pick-up circuit which may be traced from terminal a, through back contact 83 of relay R^E , wires 83^a and 84, circuit controller U^E , wires 85 and 86, winding of relay Z^E and wire 87 to terminal b. The relay is also provided with 65 a second pick-up circuit which may be traced

from terminal a, through a reverse contact on circuit controller W^G , wire 91, front contact 92 of relay Z^G , wires 93, 90 and 86, winding of relay Z^E and wire 87 to terminal b. Relay Z^E therefore becomes energized if a 70 train enters section E-F with signal r^E at proceed, or if relay Z^G becomes energized due to the entrance of a train into section G-H when the switches of crossover g are reversed to permit this train to run into section E-F. Having once been energized, relay Z^E is maintained in its energized condition as long as relay R^E is de-energized, by virtue of a stick 75 circuit which passes from terminal a, through back contact 83 of relay R^E , wires 83^a and 88, front contact 89 of relay Z^E , wires 90 and 86, winding of relay Z^E and wire 87 to terminal b.

If a train enters section H-J from section 80 G-H with the switches of crossover g in their normal positions and relay Z^G energized, the de-energization of relay R^H completes a pick-up circuit for relay Z^H , which circuit is from terminal a, through back contact 103 of relay R^H , wires 104 and 111, a 85 normal contact N on circuit controller W^H , wire 112, front contact 113 of relay Z^H , wires 114, 108 and 109, winding of relay Z^H and wire 110 to terminal b. If a train enters section 90 H-J with relay Z^E energized and the switches of cross-over h reversed, as is the case when the train enters the section from section E-F over the crossover, relay R^H becomes de-energized and relay R^H becomes energized by a circuit which passes from terminal a, through back contact 103 of track 95 relay R^H , wire 104, a reverse contact R on circuit controller W^H , wire 105, front contact 106 of relay Z^H , wires 107, 108 and 109, winding of relay Z^H and wire 110 back to terminal b thereby picking up relay Z^H . Having once 100 been energized over either of the pick-up circuits just traced, relay Z^H is subsequently held in its energized condition as long as relay R^H remains de-energized, the stick circuit being from terminal a, through back contact 103 of track relay R^H , wires 104, 111 and 115, front contact 116 of relay Z^H , wires 116^a and 109, winding of relay Z^H , and wire 110 to terminal b.

110 Associated with each stick relay Z is a coding device designated by the reference character K with a suitable exponent. Each coding device K comprises two magnets 8 and 9, and a pivoted armature 49 biased to a central position but arranged to be attracted by one or the other of the magnets. Carried by the armature 49 are movable contacts 11 and 14, which swing to one side or the other, depending upon which of the magnets 8 or 9 is attracting the armature. Referring particularly to coding device K^H , the circuit for this device is from terminal a, through front contact 117 of relay Z^H , a rectifier 10, magnets 8 and 9 of device K^H , to terminal b. The device K^H is intended to 115 120 125 130

operate on direct current, and since the source of energy, the terminals of which are *a* and *b*, is a source of alternating current, the rectifier 10 is included in the circuit for the 5 coding device to change the alternating current supplied thereto to unidirectional current. It will be seen that contact 11-11^a is arranged to short circuit magnet 9, and that contact 11-11^b is arranged to short circuit magnet 8. The contacts are so arranged 10 that when the coding device is de-energized, contact 11-11^a is closed. If, therefore, the operating circuit for device K^H becomes closed, current will be supplied to magnet 8, 15 but will be shunted around magnet 9 by contact 11-11^a. Armature 49 will, therefore, be attracted by magnet 8 to open contact 11-11^a and close contact 11-11^b. Current will then be supplied to magnet 9, and magnet 8 will be short-circuited. The magnets 8 20 and 9 are arranged to be slow acting, so that an interval of time will elapse before the increasing flux in magnet 9 will overcome the decreasing flux in magnet 8 to a sufficient degree to again reverse armature 49. At the 25 expiration of this time interval, armature 49 will swing back toward magnet 9, so that contact 11-11^b will be open, and contact 11-11^a will be closed. Another time interval will elapse before armature 49 is again 30 reversed. It follows that when the operating circuit for device K^H is closed, the armature 49 will oscillate, so that the contacts controlled by this armature are operated intermittently. The contacts 14-14^a and 14-14^b 35 are so adjusted that they are both closed when the device is de-energized. When the device becomes energized, however, these contacts are opened alternately. The parts are 40 so arranged, as indicated by the unequal shunting bands on the magnets 8 and 9, that when the device K is operated, contact 14-14^a is closed for a larger proportion of each cycle than is contact 14-14^b. For example, assuming 45 that a complete cycle of operation of the device requires one second, the contacts may be so arranged that contact 14-14^a is closed for two-thirds of a second, and contact 14-14^b is closed for one-third of a second. 50 As shown in the drawing, relays R^J and R^F are energized, the switches of crossovers *g* and *h* are in their normal positions and signals r^E and r^F are indicating stop. A circuit, 55 is therefore closed from terminal *a*, through front contact 118 of relay R^F, wire 119, a "CN" contact of circuit controller W^E, wire 133, a "CN" contact on circuit controller W^H, wire 120, contact 14-14^a of coding device K^F, wire 121, and primary 4 of track 60 transformer T^F to terminal *b*. Current is therefore supplied to the rails of section E-F by transformer T^F. Relay R^E is energized, so that relay Z^E is de-energized. The circuit 65 for coding device K^F is open at front contact 117 of relay Z^E, so that the coding device is

de-energized and contact 14-14^a is continuously closed. It follows that the current supplied to the track rails of section E-F, under these conditions, is uninterrupted. The circuit for transformer T^F may be traced from terminal *a*, through front contact 122 of relay R^J, wire 123, a "CN" contact on circuit controller W^H, wire 124, contact 14-14^a of coding device K^J, wire 125, and primary 4 of transformer T^F to terminal *b*. The current thus supplied to the rails of section H-J energizes relay R^H so that relay Z^H is de-energized and device K^J is also de-energized. Contact 14-14^a of this coding device is therefore continuously closed and the current supplied to the section H-J is uninterrupted. Another circuit is closed from terminal *a*, through front contact 122 of relay R^J, wire 123, a "CN" contact on circuit controller W^H, wire 126, a "CN" contact on circuit controller W^E, wire 127, contact 14-14^a of coding device K^H, wires 128 and 129, front contact 130 of relay R^H, wire 131, a "CN" contact on circuit controller W^E, wire 132, and primary 4 of transformer T^H, back 70 to terminal *b*. It will be seen that this circuit is closed only when the switches for both crossovers *g* and *h* occupy their normal positions and when both relays R^H and R^J are energized. The current thus supplied to section G-H by transformer T^H energizes relay R^G. Relay Z^G is therefore de-energized and coding device K^H is also de-energized. Contact 14-14^a of relay K^H is therefore continuously closed and the current supplied to the rails of section G-H is uninterrupted. 75 80 85 90 95 100 105 110 115 120 125 130

I will now assume that signal r^E is moved to the proceed position and that a train moving from left to right passes along track *d*. When this train enters section E-F, relay R^E will become de-energized, and the pick-up circuit for relay Z^E through circuit controller U^E will be closed, thereby energizing this relay. The closing of front contact 117 of this relay will energize coding device K^F, so that contact 14-14^a of device K^F will be operated intermittently. The circuit for primary 4 of transformer T^F will therefore be periodically interrupted so that current will be supplied to section E-F in accordance with the proceed code. The signal r^E will move to the stop indication as soon as the train enters the section, but relay Z^E will be held energized by its stick circuit so that the proceed code will be supplied to the train as it moves through the section. When the train leaves section E-F, relay R^E will pick up, breaking the stick circuit for relay Z^E and de-energizing this relay. Device K^F will therefore become de-energized, and the interruptions of the current supplied to section E-F will cease. With the train in the section to the right of point F, relay R^F will be de-energized so that current will flow from

terminal *a*, through back contact 118 of relay R^F , wire 134, a "CN" contact on circuit controller W^g , wire 135, a "CN" contact on circuit controller W^h , wire 136, contact 14-14^b of device K^F , wire 121, and primary 4 of transformer T^F to terminal *b*. If, now, a second train enters section E-F, passing signal r^E at proceed, relay Z^E will again be picked up, and will be held up by its stick circuit 10 after signal r^E is returned to its stop indication. The energization of device K^F , resulting from the closing of contact 117 of relay Z^E , will cause the circuit just traced for primary 4 of transformer T^F to be periodically interrupted at contact 14-14^b, so that current will then be supplied to section E-F in accordance with the caution code.

I will now assume that the switches of crossover *h* are reversed so that traffic is permitted to move from section E-F into section H-J. All "R" contacts and "CR" contacts on circuit controller W^h will therefore be closed, and all "N" contacts and "CN" contacts on this circuit controller will be open. Current will then flow from terminal *a*, through a "CR" contact on circuit controller W^h , wires 137 and 136, contact 14-14^b of device K^F , wire 121, and primary 4 of transformer T^F , back to terminal *b*. Current will also be supplied to transformer T^J , over a circuit which may be traced from terminal *a* through a "CR" contact on circuit controller W^h , wires 139, 140 and 141, contact 14-14^b of relay K^J , wire 125, and primary 4 of transformer T^J to terminal *b*. If now a train enters section E-F, passing signal r^E at proceed, relay Z^E will become energized as before and device K^F will operate to interrupt the supply of current to the primary 4 of transformer T^F in accordance with the caution code. The train will therefore be supplied with the caution code from transformer T^F as far as the crossover *h*. When the train proceeds over the crossover *h*, and enters section H-J, it will shunt relay R^H , and this will close the pick-up circuit for relay Z^H so that the coding device K^J will be set into operation. The operation of the device K^J will interrupt the current supplied to transformer T^J in accordance with the caution code. It follows that when the switches of crossover *h* are reversed to permit a train movement from point E to point J, a caution indication will be received on board a train passing along this route irrespective of the condition of the track relays connected with the rails to the right points F and J.

I will next assume all the switches are normal, that relays R^J and R^F are energized, that signal r^g indicates proceed, and that a train moving in the direction of the arrow passes this signal moving along the track *e*. The de-energization of relay R^g will complete the pick-up circuit for relay Z^g which will thereupon become energized and will com-

plete its stick circuit over its own front contact 101 and back contact 94 of relay R^g . The closing of front contact 117 of relay Z^g will energize the coding device K^H so that contact 14-14^a of this device will periodically interrupt the circuit hereinbefore traced for primary 4 of transformer T^H . Current will therefore be supplied to the rails of section G-H in accordance with the proceed code. When the train enters section H-J, the de-energization of relay R^H will complete a pick-up circuit for relay Z^H over an "N" contact on circuit controller W^g and front contact 113 of relay Z^g . Relay Z^H will therefore become energized, and will be maintained in its energized condition, as long as relay R^H is de-energized, by virtue of its stick circuit including front contact 116 of the relay Z^H and back contact 103 of relay R^H . Device K^J will therefore be energized, and contact 14-14^a of this relay will operate to periodically interrupt the supply of current to the primary 4 of transformer T^J in accordance with the proceed code. Under these conditions, therefore, when the train is in section G-H it will be supplied with the proceed code from transformer T^H , and when the train is in section H-J it will be supplied with the proceed code from transformer T^J . When the train is in section H-J, so that relay R^H is de-energized, front contact 130 of this relay will be open and back contact 130 of this relay will be closed, so that current will flow from terminal *a*, through back contact 130 of relay R^H , wire 131, a "CN" contact on circuit controller W^g , wire 132, and primary 4 of transformer T^H to terminal *b*. A following train entering section G-H, under these conditions, will therefore be supplied with uninterrupted alternating current, and so it will therefore receive a stop indication.

If relay R^J is de-energized when a train passes signal r^g at proceed, the entrance of the train into section G-H will energize device K^H as before, and current will be supplied from terminal *a* through back contact 122 of relay R^J , wire 143, a "CN" contact on circuit controller W^h , wires 140 and 144, a "CN" contact on circuit controller W^g , wire 145, contact 14-14^b of device K^H , wires 128 and 129, front contact 130 of relay R^H , wire 131, a "CN" contact of circuit controller W^g , wire 132, and primary 4 of transformer T^H to terminal *b*. Under these conditions current will be supplied to the rails of section G-H in accordance with the caution code. When the train enters section H-J, the de-energization of relay R^H will operate to energize device K^J as explained hereinbefore. Current will then flow from terminal *a*, through back contact 122 of relay R^J , wire 143, a "CN" contact on circuit controller W^h , wires 140 and 141, contact 14-14^b of device K^J , wire 125, and primary 4 of transformer T^J to

terminal *b*. Current will therefore be supplied to the rails of section H—J in accordance with the caution code. When relay R^J is de-energized, therefore, a train passing 5 along track *e* will receive current in accordance with the caution code throughout sections G—H and H—J. If a following train should enter section G—H with the first train still in section H—J, so that relay R^H is de-energized, the circuit for transformer T^H would be closed through back contact 130 of relay R^H directly to terminal *a*, so that uninterrupted current would be supplied to section G—H and the following train would 10 receive a stop indication.

I will next assume that the switches of crossover *g* are reversed to permit a movement of traffic from section G—H into section E—F. Circuit controller W^g will then 20 be reversed so that the "R" and "CR" contacts of this circuit controller are closed. If, now, a train enters section G—H, passing signal r^G at proceed, relay R^G will become de-energized so that relay Z^G will become energized, 25 and this will energize device K^H , as explained hereinbefore. The circuit for transformer T^H , under these conditions, is from terminal *a*, through a "CR" contact on circuit controller W^g , wires 146 and 145, contact 14—14^b of device K^H , wires 128 and 148, front contact 149 of relay R^E , a "CR" contact on circuit controller W^g , wires 150 and 132, and primary 4 of transformer T^H to terminal *b*. Current will therefore be supplied 30 to the rails of section G—H in accordance with the caution code. When relay Z^G became energized, it closed a pick-up circuit for relay Z^E , and the energization of the latter relay caused device K^F to be set into operation. This continues after relay Z^G opens, 35 because of the stick circuit for relay Z^E which becomes closed when the train enters section E—F and opens relay R^E . The operation of contact 14—14^a of device K^F will periodically interrupt the circuit for transformer T^F , which circuit passes from terminal *a*, through a "CR" contact of circuit controller W^g , wires 138 and 135; a "CN" 40 contact on circuit controller W^g , wire 136, contact 14—14^b of device K^F , wire 121, and primary 4 of transformer T^F to terminal *b*. The rails of section E—F will therefore be supplied with current in accordance with the caution code, so that when the train enters 45 this section it will receive a caution indication. It should be pointed out that when the train enters section E—F, thereby de-energizing relay R^E , the circuit previously traced for primary 4 of transformer T^H over front contact 149 of relay R^E becomes opened, and another circuit for this primary is closed, from terminal *a*, through wire 147, back contact 149 of relay R^E , a "CR" contact on circuit controller W^g , wires 150 and 132, and 50 primary 4 of transformer T^H to terminal *b*.

A following train entering section G—H would therefore be supplied with uninterrupted alternating current and would receive a stop indication.

I will next assume that the switches of both cross-overs *g* and *h* are reversed to permit movements of traffic from section G—H through crossover *g* into section E—F, and thence through crossover *h* into section H—J. If, now, a train moving in the direction of the arrow passes signal r^G at proceed, the de-energization of relay R^G will pick up relay Z^G and so will set device K^H into operation. The operation of this device will therefore interrupt the current supplied to primary 4 of transformer T^H , over "CR" contact of circuit controller W^g , contact 14—14^b of device K^H , and front contact 149 of relay R^E , and current will be supplied to the rails of section G—H in accordance with the caution code. The closing of relay Z^G has also caused relay Z^E to become energized, and this has caused device K^F to be set into operation as before. The operation of contact 14—14^b of this device will interrupt the circuit for primary 4 of transformer T^F , which circuit passes over a "CR" contact of circuit controller W^h , so that current will be supplied to the rails of section E—F in accordance with the caution code. When the train, moving through crossover *h* enters section H—J, the de-energization of relay R^H will complete a pick-up circuit for relay Z^H over an "R" contact on circuit controller W^h and front contact 106 of relay Z^E , so that relay Z^H will 100 become energized and will then be maintained in its energized condition by its stick circuit. Device K^J will therefore be energized and will operate to periodically interrupt the current supplied to primary 4 of transformer T^J in accordance with the caution code. It should be pointed out that when the switches of both crossovers *g* and *h* are reversed, a train traversing the route which is then set up will be supplied with current in 105 accordance with the caution code irrespective of the condition of energization of relays R^J and R^F .

If a train passes either of the signals r^E or r^G when the signal indicates stop, the corresponding stick relay Z will not become energized, because the pick-up circuit for each stick relay includes a contact *U* which is closed only when the signal indicates proceed. If 110 the stick relays do not pick up, the coding relays will not become energized, and if the coding relays do not become energized, the current supplied to the trackway will not be interrupted in accordance with one of the codes. It follows that if a train passes one of the signals which is not indicating proceed, the train will be supplied with uninterrupted alternating current throughout the stretch, and cannot receive a caution or a proceed indication.

When a train is proceeding over one of the crossovers *g* and *h*, it is necessary to supply current to the rails occupied by the train. In the form of my invention here shown, this is accomplished by dividing each of the crossovers adjacent its center with insulated joints 155. Referring for example to crossover *g*, the rails 1 and 1^a of the lower portion of the crossover are connected by means of conductors 151 and 152 attached to the rails adjacent the insulated joints 155 with rails 1^a and 1 respectively of section G—H. Insulated joints 153 are also inserted in the rails 1 and 1^a of section G—H immediately to the left of the points of connection of conductors 151 and 152, and a small impedance 154 is shunted around each insulated joint 153. It will be plain therefore that when current is being supplied to the rails of section G—H from transformer T^h, the potential drop in the impedance 154 is effective to force a current through the conductors 151 and 152 to the rails of the lower part of crossover *g*. As soon as the train moving from left to right passes the insulated joints 155, current will be supplied to the train from transformer T^g. The arrangement of parts for supplying current to a train traversing crossover *h* is similar to the parts just described for crossover *g*. Although I have herein shown and described only one form of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a stretch of railway track, a coding device controlled by traffic conditions, and comprising two normally closed contacts arranged at times to be operated intermittently so that the contacts are open for different intervals of time, a source of energy, and means for connecting said source with the rails of the stretch over a selected one of said contacts.

2. Railway traffic controlling apparatus comprising a stretch of railway track, a transformer having its secondary connected with the rails of the stretch, a repeater relay controlled in accordance with traffic conditions, a coding device controlled by traffic conditions and comprising two normally closed contacts arranged to be opened intermittently when the coding device is operated so that the contacts are closed for different proportions of a given interval of time, a circuit for the primary of said transformer including a front contact of said repeater relay and one contact of said coding device, and a second circuit for said primary including a back contact of said repeater relay and the remaining contact of said coding device.

3. In combination, a stretch of railway track, a signal for governing traffic through said stretch, coding means effective when set into operation to supply interrupted alternating current to the rails of the stretch; and means effective when a train enters said stretch provided said signal is in a predetermined position to set said coding means into operation.

4. In combination, a stretch of railway track, a signal for governing traffic through said stretch, coding means effective when set into operation to supply interrupted alternating current to the rails of the stretch, so that the rails are supplied with such current for different proportions of a given interval of time depending upon traffic conditions in advance of the stretch, and means effective when a train enters said stretch provided said signal is in a predetermined position to set said coding means into operation.

5. In combination, a stretch of railway track, a signal for governing traffic through said stretch, a switch in said stretch, coding means controlled in accordance with the position of said switch and effective when set into operation to supply interrupted alternating current to the rails of the stretch, and means effective when a train enters said stretch provided said signal is in a predetermined position to set said coding means into operation.

6. In combination, a stretch of railway track, a switch in said stretch, a coding device operated when a train enters the stretch, and means controlled by said switch and by said coding device for at times supplying the rails of the stretch with periodically interrupted alternating current.

7. In combination, a stretch of railway track, a switch in said stretch, means controlled in accordance with the position of said switch for supplying alternating current to the rails of said stretch, and means controlled by traffic conditions for at times periodically interrupting said current.

8. In combination, a stretch of railway track, a switch in said stretch, means effective when said switch is in one position to supply interrupted alternating current to the stretch so that current flows in the rails for one proportion of a given interval of time, and means effective when said switch is in a different position to supply the rails with interrupted alternating current so that current flows in the rails for said one proportion or a different proportion of said time interval depending upon traffic conditions.

9. In combination, a stretch of railway track, a switch in said stretch, two contacts arranged at times to operate intermittently so that the contacts are closed for different proportions of a given interval of time, means effective when said switch is in one position to supply current to the rails of said stretch over one or the other of said contacts depend-

ing upon traffic conditions, and means effective when said switch occupies other positions to supply current to the rails over the remaining contact only.

5 10. In combination, a stretch of railway track, a track relay connected with the rails of the stretch, a signal for governing traffic through the stretch, a stick relay controlled by said track relay and said signal, a coding device controlled by said stick relay, means for supplying alternating current to the rails of the stretch, and means controlled by said coding device for at times periodically interrupting the supply of such current.

15 11. In combination, a stretch of railway track, a track relay connected with the rails of the stretch, a signal for governing traffic through the stretch, a stick relay, means for energizing said stick relay if said track relay becomes de-energized while said signal displays a predetermined indication, means for subsequently maintaining said stick relay in its energized condition as long as said track relay remains de-energized, a coding device controlled by said stick relay, and means controlled by said coding device for supplying interrupted alternating current to the rails of the stretch.

20 12. In combination, a section of railway track, containing a switch, and means for supplying the rails of said section with train governing current periodically interrupted in accordance with one code or another depending on traffic conditions in advance of the section 25 when said switch is in normal position, and for supplying said rails with train governing current periodically interrupted in accordance with only one of said codes regardless of traffic conditions in advance of the section 30 when said switch is in the reverse position.

35 13. In combination, a section of railway track, containing a switch, and means for supplying the rails of said section with train governing current periodically interrupted in accordance with a proceed code or a caution code depending on traffic conditions in advance of the section when said switch is in the normal position, and for supplying said rails with train governing current periodically interrupted in accordance with the caution code only regardless of traffic conditions in advance of the section when said switch is in the reverse position.

40 14. In combination, a section of railway track containing a switch, a source of alternating current, an electric motor, and means controlled by said motor for periodically connecting said source with the rails of said section in accordance with one code or another depending on traffic conditions in advance of the section when said switch is in the normal position, and for connecting said source with the rails of the section in accordance with 45 only one of said codes regardless of traffic

conditions in advance of the section when said switch is in the reverse position.

15. In combination, a section of railway track containing a switch, a coding device comprising a motor and two contacts operated by said motor in accordance with two different codes, a source of alternating current, and means for connecting said source with the rails of said section through one or the other of said contacts according to traffic 70 conditions in advance of the section when said switch is in the normal position, and for connecting said source with the rails of the section through one of said contacts but not the other regardless of traffic conditions in 75 advance of the section when said switch is in the reverse position.

In testimony whereof I affix my signature.

HERBERT A. WALLACE.
